UNITED STATES PATENT OFFICE.

ALFRED TÜRTH, OF BERLIN, GERMANY, ASSIGNOR TO AUTOMATISCHE WAGEN-
EINSTEIN GESELLSCHAFT MIT BESCHRANKTER HAFTUNG, OF BERLIN, GERMANY.

ARRANGEMENT FOR MOVING AND HOLDING CAR-WINDOWS.

1,084,862.

Specification of Letters Patent.

Patented Jan. 20, 1914.

Application filed August 27, 1912. Serial No. 717,258.

To all whom it may concern:

Be it known that I, Dr. Ing. ALFRED KÜRTH, a subject of the Emperor of Austria-Hungary, and a resident of Berlin, Germany, have invented certain new and useful Improvements in Arrangements for Moving and Holding Car-Windows, of which the following is the specification.

The present invention relates to an arrangement for moving and holding car windows with one bottom and one top pressure frame, in which the window balanced by means of springs or weights is moved by means of a crank handle. By turning this crank in the one or the other direction firstly the pressure frame below holding the window is slackened and then the window is lowered and raised while the crank on being released will be returned at any position of the window, by means of a spring into its initial position. At the same time the lower pressure frame will, likewise under the action of springs, be returned into its position of rest, in which it bears against the window and will hold the same securely in the adjusted position. The top pressure frame may be so constructed, that it will either press against the window only when the same is closed, or that it will press against the window at all intermediate positions, so that a rattling of the window will by all means be avoided.

In the accompanying drawing two constructional forms of the present invention are exemplified.

Figure 1 is the one constructional form in front elevation, Fig. 2 is a longitudinal section and Fig. 3 is a cross section on an enlarged scale. Fig. 4 shows the device for moving the window and the bottom pressure frame, and Fig. 5 illustrates the connection between the bottom and the top pressure frame, which in the present constructional form is pressed against the window only when the latter is in its terminal position. Figs. 6, 7 and 8 show in three different positions a cross section through another constructional form, in which the top pressure frame is pressed against the window also at all intermediate positions.

The window F balanced in known manner is displaceable in the door frame T by means of shears S and springs t, t. The crank handle K for operating the shears and for raising and lowering the window, as

also for operating the bottom pressure frame journaled at P, is rigidly coupled to the pin O and journaled in the bearing N. On the same pin O is loosely fitted a crank A which acts by means of connecting rod B and an auxiliary shears H on the main shears S. Rigidly attached to the pin O is a cam disk E, against the circumference of which the rollers G₁ and G₂ of two rods C and D ride. These rods act on the double armed levers g, g (Fig. 3). When the cam disk is turned from the position shown in Fig. 4 to the one or the other side, the rollers G₁ and G₂ are moved farther away from the center of the disk, and thereby the ledge or sill L and the frame R connected thereto are forced away from the window toward outside, by the aid of the connecting rods C and D and the double armed levers g, g; the window will thereby be released. When the crank K is turned still farther, one of the two abutments R₁ or R₂, which are fitted to the cam disk E will, according to the direction in which the crank is turned, strike against the loose crank A, which will thereby be made to follow the rotation of the cam disk, and will by means of the rod B move the window, which owing to the pressure frame having been released, can now move freely in its guides.

If the crank K is released at any position, it will together with the cam disk E be always returned into its original position by means of a spiral spring f. In this initial position the notches in the cam disk clear the rollers G₁ and G₂ and the bottom frame R bears against the window under action of the springs s, s holding it tightly in its adjusted position. This operation is the same at all intermediate positions of the window. The only exception is the highest, closed position. The bottom part of the window frame f, (Fig. 3) or with frameless windows, the lower framing is made in form of a bearing ledge V. As soon as the window has been raised into its highest position, and the crank is released, the sill L fitted to the lower pressure frame R engages under the bearing ledge V and at the same time the upper pressure frame Q journaled at P, which is at all intermediate positions held by means of springs n, n away from the window, as evident from Fig. 5, bears against the window, by the upper pressure frame Q being dogged by the strap W at

tached to the lower pressure frame R and encircling the lower part of the top frame Q. By this means the window is prevented from rattling and is perfectly jointed, and the sill 5 ledge engaging beneath it will prevent the window from opening by itself in consequence of violent shocks. The use of this sill was induced by the recognition of the fact, that a really good and durable guide 10 for the window could only be obtained if the travel of the window in its guide remains rectilinear, so that the window need no more like heretofore be lifted from its guides and be settled down on the outwardly arranged 15 sill, and the movable sill is on the contrary pushed beneath the window, which may therefore remain in its rectilinear guides. Therefore the lower pressure frame could also be fitted to the inside of the window. 20 In this case an ordinary pressure or supporting ledge may be employed in place of the usual sill, which ledge will then have the object of supporting the window in its highest position.

25 In the constructional form shown in Figs. 6 to 8 the arrangement, as said above, is such, that the upper pressure frame will bear against the window, not only when the latter is in its highest position but at all intermediate positions, so that the window will 30 be securely held and all rattling will be prevented. This is obtained by the upper pressure frame being coupled to the lower one in such a manner, that it will be controlled in 35 a positive manner by the lower one which is operated by hand and the crank handle, so that it will be lifted from the window, contrary to the forces acting on it, only when the lower frame has been moved into the position necessary for moving the window. In the constructional form shown in the 40 said figures this coupling of the upper and lower pressure frames is obtained by the former engaging with a nose behind the latter. The dimensions are so chosen, that the lower frame will operate the upper one, when moved back for releasing the window, after it has released the window and the latter can thus be moved. The lower pressure 45 frame is moved into such position only when the window is to be moved, and must therefore be loosened. At all other positions of the frame (and therefore at all positions 50 which the said frame will have when the window is lowered either entirely or partly and is to remain in such position) it will not affect the upper frame, and the latter will be only under the action of the springs which force it against the window, so that the window is tightly held.

As may be seen from Figs. 6 to 8 the upper frame Q is under action of the springs n_1 , which tend to force it against the window F. On the lower frame the springs s act in ex- 55 actly the same sense, the same as with the

constructional form according to Figs. 1 to 5. On the upper frame Q are provided noses Q_1 , preferably at the sides, which engage over the frame R.

Fig. 6 shows the window in its highest position. The frame Q is forced by the spring n_1 against the window F, the lower frame R is forced by the spring s together with the sill L toward inside, so that the sill L serves as a support for the bearing ledge V of the 75 window F.

In Figs. 7 and 8 the crank K and its accessories have been omitted for sake of greater simplicity, and the parts are shown in the position, at which the window may be freely moved. The lower frame R has been forced toward outside by means of the bars C and D and the levers g, g (Figs. 3 and 4), contrary to the action of springs s , so that it has released the frame of the window F. 80 At the same time the lower frame R has also moved from inside toward the nose Q_1 and has thereby moved back the upper frame Q, contrary to the action of the springs n_1 , so that this frame will no more hold the window and the latter may be freely moved. 90

Fig. 8 shows the parts in the position, which they assume after the crank handle has been released while the window is standing in any position. The cam disk E (Fig. 4) has been returned into its position of rest, the bars C and D are likewise returned into their position of rest, and the lower frame R has therefore been able to follow the action of the springs s and to bear against the window frame, so that the latter is held tightly. At the same time also the nose Q_1 and with it the upper frame Q have been released, so that it can bear under action of the springs n_1 against the window frame. The 105 window will thus be tightly held both at the upper and at the lower portion of its frame, also in the intermediate positions as shown, and all rattling will be avoided.

I claim:

1. The combination of a frame, a balanced window mounted therein and movable to and from a closed position, means for moving said window, a movable pressure frame, springs acting thereon and tending to move said pressure frame in a direction toward said window whereby said window is held against movement, a crank handle for actuating said window moving means and for moving said pressure frame to release said window and a spring for returning said crank handle to its initial position independently of said means and said pressure frame. 115

2. The combination of a frame, a balanced window mounted therein and movable to and from a closed position, means for moving said window, a movable pressure frame, springs acting thereon and tending to move said pressure frame in a direction toward said window whereby said window 125

is held against movement, a rainsill carried by said pressure frame, bell cranks engaging said pressure frame, connecting rods extending from said bell cranks, a rotatable 5 cam adapted to actuate said connecting rods and said bell cranks whereby said pressure frame is moved against said springs to release the window, a lever connected with said window moving means and movable independently of said cam, abutments on said cam arranged to engage and actuate said lever as the cam is rotated whereby said window moving means is operated, a crank handle connected with said cam for rotating same, and a spring for returning said crank to its initial position independently of said window moving means and said pressure frame.

3. The combination of a frame, a balanced window mounted therein and movable to and from a closed position, means for moving said window, a movable pressure frame adapted to bear against the window to maintain it in an intermediate position, a rainsill carried by said pressure frame and arranged to extend beneath said window for maintaining it in its closed position, springs for pressing said pressure frame against said window when in an intermediate position and for moving said sill beneath said window when in its closed position, a crank handle for actuating said window moving means and for moving said pressure frame and sill to release said window and a spring 35 for returning said crank handle to its initial position independently of said pressure frame.

4. The combination of a frame, a balanced window mounted therein and movable to and from a closed position, means for moving said window, a movable lower pressure frame arranged to maintain said window in its closed position and in any intermediate position, springs acting on said

lower pressure frame and tending to move it 45 in a direction toward said window, a movable upper pressure frame, a connection between said pressure frames whereby said upper frame is pressed against the window only when said window is in its closed position, a crank handle for actuating said window moving means and for moving said lower pressure frame to release the window and a spring for returning said crank handle to its initial position independently of 50 55 said window moving means and said pressure frames.

5. The combination of a frame, a balanced window mounted therein and movable to and from a closed position, means for moving said window, a movable lower pressure frame arranged to maintain said window in its closed position and in any intermediate position, springs acting on said lower pressure frame and tending to move 60 it in a direction toward said window, a movable upper pressure frame, a connection between said pressure frames whereby said upper frame is pressed against the window only when said window is in its closed position, 70 springs for maintaining said upper pressure frame out of contact with said window when it is not in its closed position, a crank handle for actuating said window moving means and for moving said lower pressure frame to release the window and compress said last named springs and a spring for returning said crank handle to its initial position independently of 75 80 said window moving means and said pressure frames.

In witness whereof I have hereunto signed my name this 15th day of August 1912 in the presence of two subscribing witnesses.
